OTHER PUBLICATIONS

U.S. Appl. No. 29/392,702, filed May 25, 2011, entitled "An Abrasive Disc with a Distribution of Holes".

(Continued)

Primary Examiner — Patricia Palasik(74) *Attorney, Agent, or Firm* — Joseph P. Sullivan; Abel Law Group, LLP(57) **CLAIM**

The ornamental design for an abrasive disc with a distribution of holes, as shown and described.

DESCRIPTION

FIG. 1 is a perspective view of an abrasive disc according to the present design;

FIG. 2 is a front view of the abrasive disc of FIG. 1;

FIG. 3 is a back view of the abrasive disc of FIG. 1; and,

FIG. 4 is a side view of the abrasive disc of FIG. 1.
